United States Patent Office.

J. C. COOK, OF BUFFALO, NEW YORK.

Letters Patent No. 76,894, dated April 21, 1868.

IMPROVEMENT IN BOSOM-PADS.

The Schedule referred to in these Letters Patent and making part of the same.

TO ALL WHOM IT MAY CONCERN:

Be it known that I, J. C. Cook, of the city of Buffalo, in the county of Erie, and State of New York, have invented a certain new and useful Improvement in Bosom-Pads; and do hereby declare that the following is a full and exact description thereof, reference being had to the accompanying drawings making part of this specification, in which—

Figure I is a front elevation of my improved pads as applied to the person.

Figure II is a section of the same.

Like letters of reference designate corresponding parts in both figures.

The nature of my invention consists in the combination, with an elastic pad of India rubber or similar material, which may be inflated and expanded with air, of a non-elastic knit covering, made of the form and size desired for the pad when inflated, so that it will act as a check to any undue inflation of the elastic pad, and serve to retain the same in a proper and symmetrical form.

In the drawings, A A represent two India-rubber sacks, connected together by a small tube, b, of the same material, which has another tube, e, opening therein, provided with a mouth-piece and stopper, d, by which the two sacks may be inflated with air at the same time. Each of these sacks I enclose in a case or covering, composed of a knit portion, e, for the outer surface, and a disk, f, of flannel or other fabric of loose, porous texture, on the inner side of the sacks, or that next to the person, with another disk, g, of cotton, silk, or linen, over the former. The edges of these disks, with that of the knit portion, are to be sewed together, forming the case or covering for the sacks, and in such a manner that, when applied to the person, the linen or equivalent material will be next to the chest, with the flannel intervening it and the rubber of the sack, while the portion of the sacks not in contact with the person will be covered by the knit material, as represented in the drawings.

The knit covering e is made of the form and size to which it is desired to inflate the elastic sacks, and being non-elastic, or comparatively so, serves the purpose of retaining the elastic sacks in their desired form and size. Without this definitely-shaped covering, the size to which the sacks might be expanded would only be determined by the extent to which the elastic material forming the sacks could be stretched without rupture, and, after being inflated a few times, a distorted form to the pads would be the necessary result.

The two pads thus constructed I connect, in front, by an elastic webbing, h, with similar pieces, i i, attached to the outer edges, to which are fastened the tape or straps, m m, for tying or otherwise fastening around the shoulders, to retain the pads in proper position.

The flannel or other equivalent material absorbs the moisture arising from perspiration, and allows the same, from its porous nature, to escape, instead of being confined beneath the pad, as it otherwise would be, by the impervious nature of the rubber, producing a sweating and disagreeable sensation.

The employment and arrangement of the central and outer webbing, h, i i, permits free and full respiration without in any way tending to change the position of the pads. Without their use, the expansion and contraction of the chest would cause a slight lateral movement of the pads.

Their elastic nature also permits the pads to be closely fitted to the person, and remain so, without the unhealthy and unpleasant effects which unyielding straps would produce.

I do not claim broadly the construction or mode of inflating the rubber sacks, but

What I claim as my invention, and desire to secure by Letters Patent, is—

A bosom-pad, consisting of an inflatable body or sack, provided with a non-elastic covering of fibrous material, shaped to the contour and dimension desired, substantially as herein described.

J. C. COOK.
